UNITED STATES PATENT OFFICE.

EMIL REYER, OF SOUTH BEND, INDIANA.

POISON-BOTTLE INDICATOR.

SPECIFICATION forming part of Letters Patent No. 555,708, dated March 3, 1896.

Application filed September 19, 1895. Serial No. 562,978. (No model.)

To all whom it may concern:

Be it known that I, EMIL REYER, a citizen of the United States, and a resident of South Bend, in the county of St. Joseph and State 5 of Indiana, have invented certain new and useful Improvements in Poison-Bottle-Indicating Tags, of which the following is a specification.

My invention relates to a poison-indicating 10 tag to be attached to bottles or similar receptacles containing poison or dangerous drugs, medicines, chemicals, or other materials or substances which should be used or handled with care, such labels or tags having tangible 15 protuberances thereon which direct attention to the nature of the contents of the bottle.

My invention consists in making such tag or label of a thin sheet of metal upon which protuberances are struck up or otherwise 20 formed integral therewith, and which may of itself be hooked or folded to place around the neck of the bottle, thus providing a convenient and inexpensive attachment as well as a mark which may be both visually and tangibly 25 distinguishable from devices heretofore employed.

In the accompanying drawings, which illustrate my invention, Figure 1 is a perspective view of a bottle with my improved tag applied to the neck thereof; Fig. 2, a detached face or side elevation of the tag detached; Fig. 3, a cross-section through a metal blank properly cut out but not stamped to the finished form required; Fig. 4, a similar cross-section 35 through a finished tag with the prongs offset from the band or body of the tag.

The tag or label 1 is made of a sheet-metal plate stamped out with three end slits 2 and with a loop-strip 3, of reduced width, to enter 40 one of the slits 2 when the tag is placed around the neck of the bottle A, as shown in Fig. 1, and then turned or bent back upon the strip 3 to secure it thereon, the several slits being placed one alongside the other to allow more 45 or less lap and adapt the tag to bottle-necks of different sizes without having the loop-

strips of greater length than that necessary to fold over and make the loop.

The sheet-metal plate is cut or stamped out, as clearly shown in Fig. 2, with a band 4, from 50 the upper edge of which projects prongs 5, pointed or sharpened to scrape or prick the fingers if brought in contact with them, and also of sufficient length to project above the cork and distributed around the cork at such 55 distance apart that the cork may be reached and drawn out by the fingers, the prongs serving, however, as an effective barrier to prevent the cork from being withdrawn without using care and dexterity in handling both the 60 cork and the bottle.

The metal blank is first stamped out in a flat plate, as shown in Fig. 3, and then rolled, or preferably stamped, in the form of cross-section shown in Fig. 4—that is, with the 65 prongs bent bayonet-shaped, with double shoulders, to form an offset which will fit up snugly against the under side of the collar 6 of the bottle, and allow the band 4 to fit flat and snugly around the neck of the bottle and 70 the prongs be held parallel thereto.

The word "Poison" or any suitable designating-word may be used instead of the word "Caution" shown in Fig. 2.

The tag is made of scraps of tin or other 75 suitable sheet metal, and may be gilded, dipped, galvanized, plated, or bronzed in any well-known or preferred manner for the purpose either of further visual designation or for ornamentation.

I am aware that paper labels covered with a gritty substance have been placed upon the body of a bottle to indicate that its contents are poisonable, and also that a rubber band has heretofore been used upon the neck of a 85 bottle, to which are secured needles which project radially therefrom, but such devices are easily attacked and damaged by strong acids, and are moreover less durable, more expensive, and less easily applied and removed from 90 the bottle than is my device.

The tags herein shown and described may

be made of a single piece of sheet metal and is durably and easily put up in packages like the ordinary label, always ready for use, and may be both easily applied and easily removed from the neck of the bottle.

5 I claim as my invention and desire to secure by Letters Patent—

An article of manufacture, a poison-indicating tag made of sheet metal having a band 10 to encircle and interlocking ends to secure it

to the neck of the bottle, and spurs integral with the band to project upwardly therefrom around the cork, substantially as described.

In testimony that I claim the foregoing as my invention I have signed my name in the 15 presence of two subscribing witnesses.

EMIL REYER.
